CLAIM

The ornamental design for hand held gardening cultivator, as shown and described.

DESCRIPTION

FIG. 1 is a front view of the hand held gardening cultivator showing my new design;

FIG. 2 is a right side view thereof with the left side view being identical but reversed;

FIG. 3 is a rear elevational view thereof;

FIG. 4 is a top elevational view thereof; and,

FIG. 5 is a bottom elevational view thereof.

The broken line showing of a portion of a cord is for illustrative purposes only and forms no part of the claimed design.
